US00D938179S

(12) **United States Design Patent** (10) **Patent No.:** **US D938,179 S**
Wehner (45) **Date of Patent:** **** Dec. 14, 2021**

(54) CHAIR	1,646,716 A *	10/1927 Wheeler	A47D 13/105
(71) Applicant: Worldwide Creations, LLC , Clio, MI (US)	2,689,602 A	9/1954 Morgan	5/101
(72) Inventor: Scott D. Wehner , Clio, MI (US)	2,796,877 A	6/1957 Berseth	
(73) Assignee: Worldwide Creations, LLC , Clio, MI (US)	3,034,154 A	5/1962 Silverstone	
	3,130,969 A	4/1964 Groth	
	D198,779 S	8/1964 Bredon	
	3,145,990 A	8/1964 Prouty	
	D199,535 S	11/1964 Doss	
	3,186,711 A *	6/1965 Morrow	A63G 9/04
			472/118
(**) Term: 15 Years	3,213,868 A *	10/1965 Forbes	E04B 1/3441
			135/98
(21) Appl. No.: 29/714,992	3,344,443 A	10/1967 Bounell	
(22) Filed: Nov. 27, 2019	D212,801 S	11/1968 Aarnie	
(51) LOC (13) Cl. 06-01	3,528,657 A	9/1970 Krupsky	
(52) U.S. Cl. USPC D6/369	D223,444 S	4/1972 Glaser	
(58) Field of Classification Search USPC D6/334, 341, 342, 347, 360, 364, 365, D6/386, 387, 389, 643, 650, 677, 716, D6/718.1, 718.11, 344, 359, 368, 369, D6/708.16; D21/521, 797, 707, 713, 781; D23/292; D12/52, 322; D30/124, 128	D232,500 S	8/1974 McGreevy et al.	
	D232,957 S	9/1974 Kehelin	
	3,902,264 A	9/1975 Radig	
	D243,044 S	1/1977 Pathman	
	4,000,749 A	1/1977 Busco	
	4,047,752 A	9/1977 Rohr
